KENNEL CLOSURE

Charles E. Poovey, Charlotte, N. C.

Application January 24, 1949, Serial No. 72,335

1 Claim. (Cl. 160—179)

1

This invention relates to kennels, or any other type of animal enclosures having an opening therein through which an animal may be free to pass and repass and more especially to a closure for the said opening and means for securing said closure to the kennel or the like to cover the opening.

The primary object of this invention is to provide a closure for an opening of a kennel or the like comprising a rectangular framework defining an opening in which a fabric sheet is disposed, the fabric sheet being split from the upper to the lower end of the framework and the proximate portions of the fabric sheet overlapping each other and their proximate portions having hems therein in which are disposed coiled springs the upper end of which are fixed to the upper portion of the framework and the lower ends of the coiled springs being flush with the upper edge of the lower portion of the framework and as the animal pushes against the junction points of the fabric sheets, the coiled springs will be spread apart from each other along with the proximate portions of the fabric sheets, thus permitting the animal to pass therethrough, after which the coiled springs tend to assume their normal vertical pending positions which will again close the opening through which the animal has passed.

It is another object of this invention to provide a main framework of the type described and which has an auxiliary framework hingedly secured to the lower portion thereof and releasably secured at the opposite sides thereof to the main framework. Between the main framework and the auxiliary framework the edges of the fabric material may be clamped, thereby permitting for ease of replacement of the fabric material in the event that it becomes worn or decayed or for laundering purposes or for any other reason.

Some of the objects of the invention having been stated, other objects will appear as the description proceeds, when taken in connection with the accompanying drawings, in which—

Figure 1 is an isometric view of the kennel or the like showing the improved closure member applied thereto;

Figure 2 is an enlarged elevation of the closure member with parts broken away and showing a portion of the front wall of the kennel to which the closure is secured;

2

Figure 3 is a sectional plan view taken substantially along the line 3—3 in Figure 2;

Figure 4 is an isometric view of the closure member removed from the kennel and showing an auxiliary frame hinged to the bottom of the closure member and omitting the fabric material from the same;

Figure 5 is an enlarged vertical sectional view being taken substantially along the line 5—5 in Figure 2.

Referring more specifically to the drawings numeral 10 broadly designates a kennel, or any other type of animal enclosure of which a side wall 11, a front wall 12 and a roof 13 are visible in Figure 15 1. The front wall 12 has a substantially rectangular opening 13 therein (Figure 3) and it is this opening 13 that this closure member, to be presently described, is adapted to close.

The numeral 20 broadly designates the closure 20 member comprising side rails 21 and 22 and upper and lower rails 23 and 24, respectively. The side rails and the upper and lower rails may be one piece or they may be joined together in any suitable manner as desired.

25 The upper rail 23 has a thickened portion 25 extending longitudinally at the upper edge thereof and the lower rail 24 is of the same thickness as the thickened portion of the rail 23, the side rails 21 and 22 being of the same thickness as the thin portion of the top rail 23. An auxiliary framework comprising side rails 30 and 31 and an upper rail 32 is adapted to be secured against the side rails 21 and 22 and the thin portion of the upper rail 23, by means to be later described.

30 35 The lower ends of the side rails 30 and 31 of the auxiliary framework are hingedly secured as at 33 to the bottom rail 24. The side rails 30 and 31 each has a slot 35 therein and the upper rail 32 has a slot 36 adjacent each end thereof.

40 45 The side rails 21 and 22 and the upper rail 23 are adapted to be slidably penetrated by screws 37 which project a substantial distance forwardly of the front surface of the side rails 21 and 22 and the thin portion of the upper rail 23. When the auxiliary framework is swung into a closed position against the fixed framework the screws 37 loosely penetrate the slots 35 and 36 in the auxiliary framework.

However, before the auxiliary framework, comprising members 30, 31 and 32 is swung into

3

closed position, sheets of fabric material 40 and 41 are mounted against the side rails 21 and 22 and the thin portion of the upper rail 23, these sheets of fabric material being cut away at their outer edges as at 43 to clear the screws 37. It will be noted that the side rails 23 of the fixed framework are provided with longitudinally extending grooves 45 while the side rails 30, 31 and the upper rail 32 of the auxiliary framework are provided with projections extending longitudinally of each of these said last-named members and which coincide with the grooves 45 in the members 21, 22 and 23.

By referring to Figures 3 and 5 it may be observed that when the auxiliary frame, comprising members 30, 31 and 32, is swung into position against the fixed frame, comprising members 21, 22 and 23, the outer and upper portions of the sheets of fabric material 40 and 41 are interlocked by the coinciding grooves 45 and the projections 46 in the fixed frame member and the auxiliary frame member respectively. It is thus seen that the sheets of fabric material 40 and 41 are locked between the fixed frame member and the auxiliary frame member and each of the screws 37 is provided with a wing nut 47 which may be driven home after the frames and the sheets of fabric material are assembled.

Now, when it is necessary to replace the sheets of fabric material 40 and 41, for any reason, it is merely necessary to loosen the wing nuts 47, swing the auxiliary frame, comprising members 30, 31 and 32, outwardly at its upper end and then the sheets of fabric material 40 and 41 may be easily removed or replaced.

Referring to Figures 2 and 3 it will be noted that the proximate portions of the sheets of fabric material 40 and 41 overlap each other and are hemmed at their free edges by a line of stitches 49 thus forming tubular portions 50 and 51, respectively. Secured, as at 53, to the upper rail 23 of the fixed framework are the upper ends of coiled springs 54 and 55. These coiled springs 54 and 55 are preferably of a flat wire material. However, it is to be understood that any type of coiled spring may be used in this structure.

In assembling the sheets of fabric material 40 and 41 to the closure member 20, the tubular portions 50 and 51 of the respective sheets of fabric material 40 and 41 are slid upwardly around the lower ends of the coiled springs 54 and 55, respectively, until the sheets 40 and 41 assume the positions shown in Figure 2 and it is thus seen that the coiled springs 54 and 55 are surrounded by the tubular portions 50 and 51 of the sheets of fabric material 40 and 41, respectively. The lower ends of the coiled springs 54 and 55 terminate a slight distance above the top edge of the bottom rail 24 thus leaving the bottom ends of the coiled springs 54 and 55 free to move inwardly and outwardly with respect to the closure 20.

To facilitate the mounting of this closure member 20 on the front wall 12 of the kennel 10, upper and lower horizontally disposed bars 57 and 58, respectively, are secured in any suitable manner to the front walls of the kennel 10, these members 57 and 58 being spaced apart from each other a distance equal to the length from the upper end to the lower end of the closure member 20. The thickened portion 25 of the upper rail 23 of the fixed framework has plates 60 secured to the front surface thereof as by screws 61 and the upper portions of these plates 60 project above the upper surface of the rail 23 and are slotted as at 62 to slidably receive a hooked

4

portion 63 of a plate 64 secured as by screws 65 to the upper bar 57, as a result of which the closure member 20 depends from the bar 57.

The lower bar 58 is provided with turn buttons 70 oscillatably secured as at 71 to the same and these turn buttons 70 serve to lock the closure member 20 against the front wall 12 of the kennel 10, it being understood that the size of the opening 13 will be somewhat smaller than the over all size of the closure member 20.

In order to prevent a larger animal than desired from passing through the opening defined by the closure member 20, a horizontally disposed cross bar 74 is provided, as well as vertically disposed bars 75, the bars 75 being spaced apart from each other any desired distance to accommodate the size animal that it is desired shall pass through the closure member 20. Opposite ends of the cross bar 74 are secured, as by screws 76, to the side rails 30 and 31 and opposite ends of the vertically disposed rods 75 are secured, as by screws 77, to the upper cross bar 32 and the lower rail 24, it being understood that these rods 74 and 75 may be secured at each end thereof in any desired position to accommodate the size of animal that it is desired shall pass through the opening in the closure member 20.

Now, when an animal desires to pass through the opening in the closure 20, the animal merely has to bump its head against the canvas sheets 40 and 41, preferably at their junction points and they will be spread apart from each other at their lower ends sufficiently to permit the animal to pass through the opening and, after the animal has passed through the opening in the closure 20, the coiled springs 54 and 55 will inherently cause the proximate portions of the sheets of fabric material 40 and 41 to assume their original position. This will be the case regardless of which direction the animal passes between the proximate portions of the sheets of fabric material 40 and 41.

It is thus seen that I have provided a closure member for animal kennels and the like which may be mounted on the same which may be operated by the animal, which is a particularly favorable feature during cold weather.

In the drawings and specification there has been set forth a preferred embodiment of the invention, and although specific terms are employed, they are used in a generic and descriptive sense only, and not for purposes of limitation, the scope of the invention being defined in the claim:

I claim:

A closure member for openings in kennels and the like comprising a framework, a pair of sheets of fabric material, the proximate edges of which overlap each other, means for securing the top edge of the sheets of fabric material to the framework at the top edge of the opening in the kennel, the lower ends of the sheets being free to swing in any direction, the overlapping portion of the sheets of fabric material being hemmed to thus form tubular portions at the proximate edges thereof, a coiled spring mounted within the hemmed portion of each of said sheets of fabric material, the hem of one sheet of fabric material being disposed in overlapping relation to the hem in the other sheet of fabric material, means securing the upper ends of said coiled springs to the top portion of the framework at spaced points disposed along the axes

of the springs so that the coiled springs will depend from the upper wall of said opening, the lower ends of the coiled springs being free for swinging movement, whereby upon the proximate edges of the sheets of fabric material being engaged by the nose of an animal they will be forced apart from each other to permit the animal to pass therebetween and whereby, upon the animal having passed between the proximate edges of the sheets of fabric material the 10 weight of the coiled springs will urge the proximate edges of the sheets of fabric material to original overlapping position.

CHARLES E. POOVEY.
